D. H. MELOCHE

METAL MOLD

Original Filed Oct. 2, 1922

DANIEL H. MELOCHE
INVENTOR.

BY

Stanley M. Meloche
ATTORNEY.

UNITED STATES PATENT OFFICE.

DANIEL H. MELOCHE, OF DETROIT, MICHIGAN, ASSIGNOR TO EARL HOLLEY, OF DETROIT, MICHIGAN.

METAL MOLD.

Application filed October 2, 1922, Serial No. 591,725. Renewed February 23, 1924.

To all whom it may concern:

Be it known that I, DANIEL H. MELOCHE, a citizen of the United States, residing at 2241 Gladstone Ave., Detroit, in the county 5 of Wayne and State of Michigan, have invented certain new and useful Improvements in Metal Molds, of which the following is a specification.

This invention relates to a metal mold 10 specially adapted for the casting of cast iron pistons.

In the manufacture of cast iron pistons it is extremely desirable to obtain uniform 15 hardness of the rubbing surface and also to control the degree of hardness to correspond to the hardness of the cylinder wall so that the life of the pistons and the wall may be equally long.

The figure shows a cross section elevation 20 of the mold showing a core and casting in place.

The mold consists of two similar parts A and B enclosing a baked dry sand core C which is provided with a conical concentric 25 sprue or entrance D. Horizontal rectangular gates E and F lead out from the bottom of the sprue into the center of the piston bosses G and H.

Owing to the size of the core C no risers 30 are required as the mold is vented through the core. The core is located and locked in place by means of a shoulder J and a conical portion K which is provided with a large surface L exposed to the air. The surfaces 35 of the dry sand core C, against which the iron is cast, are protected by a coating preferably of magnesium oxide as set forth in my co-pending application, Serial No. 548,475, filed March 31, 1922. The magnesium oxide is applied, gluten being used as a 40 binder and water as a carrier. The core is of course dried after being coated. The surface of the molds are also protected. The particular coating that has been found best 45 for this purpose being the coating of fire clay using soluble water glass as a binder, as set forth in my co-pending application Serial No. 581,239, filed Aug. 11, 1922. A coating of lamp black is superimposed on 50 the coating of soluble silicate, the function of this coating being described in my co-pending application, Serial No. 579,927, filed Aug. 5, 1922.

The broken line indicates the arrangement of the core extended to give the increased head required when casting non-ferrous metals instead of cast iron. 55

The shoulder or ledge J provides a support for the core C. The inclined or conical face K, which is inclined at a re-entrant angle with the mold, prevents the core floating upwards under the ferrostatic head of the molten iron flowing in at D. 60

What I claim is:

1. In a metal mold adapted to the casting 65 of an internal combustion engine piston, a horizontal shoulder, a re-entrant conical face above said shoulder, a dry sand core resting on said shoulder and prevented from rising by said re-entrant conical face. 70

2. In a metal mold adapted to the casting of an internal combustion engine piston, a horizontal shoulder, a re-entrant conical face above said shoulder, a dry sand core resting on said shoulder and prevented from 75 rising by said re-entrant conical face, a sprue and gate within said core. 75

3. In a metal mold adapted for the casting 80 of a piston having bosses, a shoulder, a conical face above said shoulder, a dry sand core resting on said shoulder and located by said conical face, a sprue within said core, a gate leading from said sprue to the cavity corresponding to the said piston bosses. 80

4. In combination with a sectional metal 85 mold adapted for the casting therein of automobile engine pistons head downwards, a cylindrical core having a re-entrant shoulder locating said core in said mold and preventing it rising in the mold under the 90 ferro-static head of the iron cast therein. 90

5. In combination with a sectional metal mold adapted for the casting therein of an automobile type of piston head downwards, said piston having wrist pin bosses integral 95 therewith; a cylindrical dry sand core within said mold, a sprue within said core, gates leading from said sprue to a cavity corresponding to the said piston bosses, a re-entrant shoulder on said core, a corresponding shoulder on said mold whereby the core is located within said mold and prevented from rising therein under the ferro-static 100 head of the metal cast therethrough. 100

In testimony whereof I affix my signature.
DANIEL H. MELOCHE.
